RAILWAY TRAFFIC CONTROLLING APPARATUS

Frank H. Nicholson, Edgewood, Pa., assignor to
The Union Switch & Signal Company, Swiss-
vale, Pa., a corporation of Pennsylvania

Application May 27, 1933, Serial No. 673,209

13 Claims. (Cl. 246—63)

My invention relates to railway traffic controlling apparatus, and particularly to apparatus of the type comprising train carried train controlling means governed by energy received from the track rails.

A feature of my present invention is the provision of apparatus for superposing on the usual direct current signal controlling track circuit an uninterrupted or non-coded alternating current under certain traffic conditions, and for superposing an interrupted or coded alternating current under other traffic conditions. The train carried apparatus is selectively responsive to the coded and noncoded alternating current. In systems of this type heretofore proposed coded alternating current has been employed under clear traffic conditions and non-coded current employed under caution or the more restrictive traffic conditions. In such former systems code operation of the trackway equipment is continuously required, or at least is required for the major portion of the time. Furthermore, in such systems code operation of the train carried apparatus is also required for the major portion of the time a train is travelling over the equipped trackway. A further feature of my present invention is the provision of apparatus both on the trackway and on the train wherewith code operation is required only for the traffic condition least encountered in railway service, the arrangement of the apparatus being such that a false clear indication will not result from a failure of the coding apparatus. Code operation being thus reduced to a minimum time interval, longer life and reliability for such apparatus is assured, and the usual common type of relays may be employed to thereby greatly reduce the first cost and maintenance of such systems. A still further feature of my invention is the provision of apparatus for adding a third cab signal indication to the single element two-position cab signal now in use on many of the railroads in connection with train brake controlling equipment. The addition of this third cab indication serves to reconcile the present two-indication cab signal with the standard three-indication wayside signal system. Other features and advantages of my invention will appear as the specification progresses.

I will describe one form of trackway apparatus and one form of train carried apparatus embodying my invention, and will then point out the novel features thereof in claims.

In the accompanying drawings, Fig. 1 is a diagrammatic view illustrating one form of trackway apparatus embodying my invention. Fig. 2 is a

diagrammatic view showing one form of train carried apparatus suitable for cooperating with the trackway apparatus of Fig. 1 and also embodying my invention.

In both of the drawings similar reference characters refer to similar parts.

Referring first to Fig. 1, the reference characters 1 and 1^a designate the traffic rails of a stretch of railway over which traffic normally moves in the direction indicated by the arrow. 10 These traffic rails are divided by means of the usual insulated rail joints 2 into a plurality of successive track sections A—B, B—C, etc., the track section B—C being subdivided at B¹ to form the subsections B—B¹ and B¹—C. Each track section 15 and subsection is provided with a standard direct current track circuit which comprises the traffic rails with a battery 3 connected across the rails at the exit end of the section, and a relay R, with an exponent corresponding to its location, connected across the traffic rails at the entrance end of the section. Between the track battery 3 and one of the traffic rails is inserted the secondary winding 4 of a track transformer T with an appropriate exponent, a customary impedance 5 20 being also inserted in the connection to limit the current flow. The primary winding 13 of each track transformer T is supplied at times with uninterrupted or non-coded alternating current, and at other times the alternating current is periodically interrupted or coded. The manner of governing the supply of alternating current to the track transformers will appear later in the description.

In accordance with the usual practice each 35 track section is preferably provided with a wayside signal designated by the reference character S with an exponent corresponding to the location. These signals may be of any standard form and are here shown as semaphore signals each capable 40 of displaying a clear, an approach and a stop indication. It will be understood that my invention is not limited to any specific form of wayside signals and position light, color light, or search light signals may be employed equally as well as the 45 semaphore signals should it seem desirable to do so. As a matter of fact, my invention does not require wayside signals, and, as will appear when the operation of my system is described, the wayside signals may be omitted. The circuits for 50 controlling the signals S form no part of my present invention and are not shown in Fig. 1 for the sake of simplicity. For present purposes, it is deemed sufficient to say that any of the well-known standard arrangements of control circuits 55

may be provided, wherewith each signal is controlled in such a manner that when the immediate section in advance is occupied, the signal indicates stop; when the immediate section is unoccupied and the second section in advance is occupied, the signal indicates approach; and when the immediate section and the second section in advance are both unoccupied, the signal indicates clear.

Associated with each signal S are two circuit controllers designated by the reference characters W and X, respectively, with exponents corresponding to the location. Each circuit controller W and X occupies one position when the associated signal indicates stop, a second position when the signal indicates approach, and a third position when the signal indicates clear. To put it another way, each of the controllers W and X occupies one position when the immediate section in advance is occupied, a second position when the immediate section in advance is unoccupied and the second section in advance is occupied, and a third position when the immediate section and the second section in advance are both unoccupied. It is evident, therefore, that the positions of these controllers W and X are made to correspond with different traffic conditions in advance. When semaphore wayside signals are provided as shown in Fig. 1, the usual mechanism for the signal forms a convenient means for operating the controllers. In the event some form of light signal is provided, then these controllers W and X would be operated by the usual signal controlling relays, and in the event no wayside signals are provided, the controllers W and X would be operated by relays governed by traffic conditions in advance in the manner pointed out above.

Each track section is further provided with a normally inactive code transmitter designated by the reference character CT with an exponent corresponding to the location. These code transmitters may take different forms and are here shown as a mechanically oscillating type preferably of a structure similar to that disclosed and described in the United States Letters Patent 1,858,876, issued May 17, 1932, to Paul N. Bossart, for Coding apparatus. It is deemed sufficient for this specification to give but a brief description of these code transmitters. Referring to the transmitter CTA, for example, the field structure J has mounted between its two poles P₁ and P₂ an armature AH pivoted at O so as to swing freely. The armature AH is normally biased to the position shown, that is, to the position illustrated in Fig. 1, and has two circuit controlling members 8 and 9 operatively associated therewith, which members normally engage the contacts 14 and 11, respectively. A field winding 6 of the code transmitter CTA is provided with a circuit extending from the positive terminal of a convenient source of direct current such as a battery 75, over controller WA when moved to its position corresponding to the stop indication of signal SA, wire 10, contact 14, contact member 8, winding 6 and to the opposite terminal of battery 75. It follows that the winding 6 is energized whenever the signal SA indicates stop.

With field winding 6 energized, the armature AH will be rotated in a clockwise direction as indicated by the arrow. After a small movement of armature AH, the contact member 8 will disengage the contact 14 to open the circuit just traced and the field winding 6 will be deenergized. Armature AH will rotate a little farther

and then its movement will be reversed due to the bias and will swing backward to bring contact member 8 again into engagement with contact 14 to reenergize the field winding 6. The armature AH will swing slightly past its normal position due to the inertia of its parts and it will then again rotate in a clockwise direction due to the influence of the field winding 6. It is clear that as long as the signal SA indicates stop the armature AH will oscillate at its natural period, the period of oscillation being determined by its biasing and the weight of its parts. Although the period of oscillation may be any convenient frequency, I shall consider it to be 60 cycles per minute. As stated above, the contact member 9 is operatively connected with the armature AH, and hence contact member 9 will oscillate between the right-hand contact 11 and a left-hand contact 12 at the code frequency of 60 cycles per minute as long as the code transmitter CTA is active.

The contact member 9 governs the supply of train governing alternating current to the track transformer TA. Non-coded alternating current is normally supplied to the primary winding 13 of the track transformer TA by a circuit extending from the BX terminal of any convenient source of alternating current such as the secondary winding of a line transformer not shown, contact member 9, right-hand contact 11, controller XA occupying the position corresponding to either the clear or approach indication of signal SA, primary winding 13 and to the opposite terminal CX of the source of alternating current. At such time as signal SA indicates stop and the code transmitter CTA is rendered active as described hereinbefore, the primary winding 13 of transformer TA receives current from the BX terminal of the source of alternating current, over contact member 9, left-hand contact 12, controller XA and winding 13 to the opposite terminal CX of the source of alternating current. It follows that as long as traffic conditions in advance of location A are such that signal SA indicates either clear or approach, the code transmitter CTA is inactive and non-coded alternating current is superposed on the direct current track circuit for the section to the left of location A. When traffic conditions in advance of location A are such as to cause signal SA to indicate stop, the code transmitter CTA is rendered active and the alternating current superposed on the direct current track circuit for the section to the left of location A is coded at the frequency of 60 cycles per minute. The alternating current may be of any convenient frequency, such, for example, as 100 cycles per second. The supply of alternating current to each of the remaining track transformers is controlled by the associated circuit controller X and code transmitter in the same manner as explained for transformer TA. In connection with the track transformer TB₁ located at the cut section location B₁, it is supplied with alternating current in parallel with the track transformer TC at the exit end of the section B—C as will be readily understood by an inspection of Fig. 1. The connection to the primary winding 13 of transformer TB₁ is also controlled by a front contact 15 of the track relay RB₁.

As shown in Fig. 1, the section to the right of location C is occupied by a train indicated diagrammatically at V. The track rails for that portion of the section to the rear of train V are deprived of both track circuit current and train

controlling current by the shunting effect of the wheels and axles of train V. Relay RC is therefore deenergized and signal SC indicates stop, causing the controllers WC and XC to occupy their corresponding positions. Under these conditions the circuit to the field winding 6 of the code transmitter CTC is closed at the controller WC and that transmitter is active. Controller XC being now closed to complete the connection from the left-hand contact 12 of code transmitter CTC, both track transformers TC and TB¹ are supplied with coded alternating current. The signal SB indicates approach and the controller WB is open and the code transmitter CTB is inactive. Controller XB is closed to complete the circuit for supplying uninterrupted alternating current to the track transformer TB. Signal SA indicates clear so that controller WA is open and code transmitter CTA is inactive. Controller XA is closed to complete the circuit for supplying uninterrupted alternating current to the track transformer TA.

The section to the left of location A is occupied by a second train indicated diagrammatically at V^a. For the purpose of controlling the train carried apparatus of train V^a by the alternating current superposed on the direct current track circuit the train V^a is provided with a receiver designated in general by the reference character M. Receiver M comprises two magnetizable cores 16 and 17 carried on the train in advance of the forward axle and located in inductive relation with the two traffic rails 1 and 1^a, respectively. Core 16 is provided with a winding 18 and core 17 is provided with a winding 19, the windings 18 and 19 being connected in series in such manner that the voltage induced therein by alternating current flowing in opposite directions in the traffic rails at an instant are additive.

Referring to Fig. 2, the windings 18 and 19 are connected through a condenser 20, with the primary winding 21 of an autotransformer T2. The windings 18 and 19 and the condenser 20 are tuned to series resonance at the frequency of the alternating current supplied to the traffic rails which I have assumed to be 100 cycles per second. The secondary winding 22 of the autotransformer T2 is tuned to parallel resonance at the frequency of the alternating current by means of a condenser 23. The resonant voltage at the terminals of condenser 23 is amplified by two electron tube amplifiers PJ2 and PJ4. The filaments of these tubes are connected in series with a ballast lamp 24, two control resistances 25 and 26 and a reactor 27, and are supplied with current from a suitable source such as the usual headlight generator HG. The reactor 27 constitutes a choke to suppress the commutator ripples in the current supplied by the generator HG. The secondary winding 22 of autotransformer T2 is connected across the grid and filament of the tube PJ2 through the resistance 25 and a comparatively high resistance 29.

The plates of the electron tubes PJ2 and PJ4 are provided with a comparatively high unidirectional electromotive force from a suitable source such as the high potential winding 34 of a dynamotor DM, having a low potential winding 35 and a field winding 36 constantly supplied with energy from the generator HG. The high potential winding 34 has its positive terminal connected with the plate of the tube PJ2 through a reactor 37, plate 31 of a condenser 76, and a second reactor 38; and with the plate of the tube PJ4 through reactor 37, condenser plate

81 and a reactor 39. The negative terminal of winding 34 is connected directly to the negative lead of the filament circuit. The second plate 33 of condenser 76 is made an integral part of the filament circuit. The reactor 37 and the condenser 76 thus form a filter for bypassing the commutator ripples of the high potential electromotive force away from the electron tubes. The various elements of this filter being made an integral part of the associated circuits, this unit 10 operates on the closed circuit principle. The function of this filter will also appear later. 11 is the usual grounding condenser associated with the filament circuit, one plate 79 being made an integral part of the filament circuit and the second plate 80 being connected with ground as shown in Fig. 2. The plate of tube PJ2 is also connected through a condenser 49 and a resistance 41 with the negative lead of the filament circuit, the grid of tube PJ4 being connected between the resistance 41 and condenser 49. It is clear, therefore, that tubes PJ2 and PJ4 and the associated apparatus comprise an amplifier of the well-known choke coil type.

The energy delivered by tube PJ4 is supplied to the primary winding 42 of a transformer T3 which is connected across the plate and filament of that tube, a blocking condenser 43 being connected in series and a tuning condenser 44 being connected in parallel with the primary winding 42. The secondary winding 45 of transformer T3 is connected with the input terminals of a full-wave rectifier 46, the output terminals of which are connected with the winding of a relay MA. It follows that alternating currents flowing in the traffic rails 1 and 1^a create in the windings 18 and 19 an alternating current which is amplified by the tubes PJ2 and PJ4 and create in the secondary winding 45 of transformer T3 an alternating current which is rectified to unidirectional current by the rectifier 46 and which serves to energize relay MA. The relay MA is preferably a direct current quick-acting neutral relay and hence as long as alternating current is continuously picked up from the traffic rails, the relay MA is energized continuously. With the alternating rail current coded, the relay MA releases at the termination of each code impulse and picks up at the beginning of the next code impulse. That is to say, relay MA is picked up continuously as long as the train controlling current is a non-coded alternating current, and is operated at the code frequency when the train controlling current is coded.

The autotransformer T2 and condenser 20 operate as a filter to prevent energization of the relay MA by stray currents of a frequency different from that of the train controlling current. The reactor 37 and condenser 76 operate as a bypass filter to bypass the high frequency commutator ripples in the high electromotive force supplied to the plate circuit of the electron tubes to prevent such pulsations being amplified and then rectified at the rectifier 46 to energize the relay MA. The reactor 27 operates as a choke coil to prevent the commutator ripples of the current supplied to the filament circuit from being amplified and then rectified to energize the relay MA. As pointed out above, the condensers 76 and 77 are each preferably of a construction such that their respective plates become an integral part of the associated circuit whereby these units operate on the closed circuit principle.

A second train carried relay designated by the reference character L is provided, and is governed 75

by the train controlling current of the trackway equipment in the following manner. The top terminal of the primary winding 47 of a transformer T4 is connected with the positive terminal 5 of the generator HG over the front contact 48 of relay MA, and the bottom terminal of the primary winding 47 is connected with the positive terminal of generator HG over the back contact 49 of relay MA, a center tap of the primary winding 47 being connected with the negative terminal 10 of generator HG. It follows that at such time as relay MA is picked up continuously or is deenergized continuously, the top half or the bottom half of the primary winding 47, as the 15 case may be, is steadily excited with direct current and no voltage is induced in the secondary winding 99 of the transformer T4. The alternate excitation of the top and bottom halves of the primary winding 47 in response to code operation 20 of the relay MA will, however, induce an alternating voltage in the secondary winding 99, the frequency of which will correspond to the code frequency at which the relay MA is operated. A portion of the secondary winding 99 is 25 connected to the input terminals of a full-wave rectifier 50, the output terminals of which are connected with the winding of the relay L. A spark arresting condenser 51 is connected across the winding 99 to reduce the sparking at the 30 contacts 48 and 49 on relay MA. It is clear that as long as non-coded alternating current is picked up from the traffic rails or no current is received by the train carried equipment, the relay L is deenergized, and when the alternating current 35 picked up from the traffic rails is coded, the relay L is picked up continuously. Relay L is preferably slow releasing in character to prevent its being released from one code impulse until the next.

40 The train is provided with a visual cab signal CS having three lamps G, Y, and R, each capable of displaying a distinctive indication. For example, the lamp G displays a green light, the lamp Y a yellow light and the lamp R a red light.

45 Referring now to the relays MA and L, it is to be noted that when relay MA is energized and relay L is deenergized, current will flow from the positive terminal of the generator HG over wire B32, front contact 48 of relay MA, back contact 50 52 of relay L, wire 81, lamp G, wire 88, front contact 54 of relay MA, and thence to the negative terminal of generator HG. The lamp G will now be illuminated. When relay L is energized, current will flow from the positive terminal of the generator HG over wire B32, front contact 61 of 55 relay L, wire 62, lamp Y, wire 89, front contact 63 of relay L, and thence to the negative terminal of the generator HG to illuminate lamp Y. Again, when both relays MA and L are deenergized, current will flow from the positive terminal of generator HG over wire B32, back contact 49 of relay MA, back contact 64 of relay L, wire 65, lamp R, wire 90, back contact 66 of relay MA, and thence to the negative terminal of generator HG, to illuminate lamp R. It follows that clear traffic conditions which cause relay MA to be energized continuously and relay L to be deenergized will cause the cab signal to display a green light. Approach traffic conditions which cause relay MA to be operated at the code frequency and relay L to be energized continuously will cause the cab signal CS to display a yellow light, and stop traffic conditions at which time no current is supplied to the train will cause both relays MA and L to be 70 75

deenergized and the cab signal to display a red light.

It is desirable to audibly call the attention of the engineman to a change of the visual indication of the cab signal resulting from a change 5 in traffic conditions, especially when such change represents a more restrictive condition. This is preferably accomplished by an air whistle designated by the reference character WS and controlled by a magnet valve designated as a whole 10 by the reference character H. As shown diagrammatically, fluid pressure is supplied to a chamber 53 through a pipe 28 connected with a suitable source of fluid pressure not shown. At such time as the winding 67 of the magnet valve 15 H is energized, a valve 68 is seated and the pressure is shut off from the pipe 69 leading to the whistle WS and the whistle is silent. When the winding 67 is deenergized, the valve 68 is lifted and the fluid pressure in chamber 53 escapes to 20 the atmosphere through the pipe 69 and the whistle WS causing the whistle to blow. For reasons to appear hereinafter a whistle delay 25 WD is connected in the pipe 69 with the result that there will be a slight delay between the time 25 the winding 67 is deenergized and the sounding of the whistle WS. This whistle delay WD shown as a rectangle in series with the pipe 69 is a pneumatic device for preventing the whistle from blowing until a given pressure is built up. 30 This whistle delay may take different forms and it need not be considered further inasmuch as its specific structure forms no part of my present invention.

In order that the engineman may silence the 35 whistle by acknowledging the change in the indication of the cab signal the train carried equipment is further provided with two stick relays SP and RP and an acknowledging switch ACK. The relay SP is a direct current neutral relay 40 and is provided with slow-releasing characteristics. The relay RP is a double winding direct current neutral relay capable of closing its front contacts when either of its two windings is energized.

Again, referring to the relays MA and L, it will be noted that with relay MA picked up continuously and the relay L down, current will flow from the positive terminal of generator HG over wire B32, front contact 48 of relay MA, back contact 50 55 52 of relay L, wires 87 and 55, back contact 56 of the relay RP as that relay is normally deenergized, wire 57, winding 67 of magnet valve H, controller 58 of the switch ACK and normally closed, wire 91, back contact 59 of the relay SP 55 which is also normally deenergized, a second back contact 60 of relay RP, wires 92 and 88, front contact 54 of relay MA, and thence to the negative terminal of the generator HG, and magnet valve H will be energized. That is to say, clear 60 traffic conditions that cause relay MA to be picked up continuously, result in the magnet valve H being energized and the whistle WS being silent. Assuming that the traffic conditions change from clear to approach with the result 65 that the relay MA is code operated and relay L is picked up, the above-traced circuit for winding 67 will be open at the back contact 52 of relay L and consequently magnet valve H will be deenergized and after a slight delay caused by the 70 whistle delay WD, the audible signal WS will be sounded to call the engineman's attention to the change in the indication of the cab signal.

The winding 67 of the magnet valve H may be reenergized and the whistle WS silenced in the 75

following manner. The engineman will actuate the acknowledging switch ACK to the position for closing a controller 70, and will then restore the switch to its normal position where the controller 58 is closed. During the interval that the controller 70 is closed, current will flow from the positive terminal of the generator HG over wire B32, back contact 49 of relay MA when that relay releases at the end of the first code impulse, 10 wire 71, controller 70, wire 72, top winding of relay RP, and thence to the negative terminal of the generator HG, and relay RP will be picked up. At the same time current will flow over this same circuit just traced up to wire 72, and thence 15 through the winding of relay SP, and to the negative terminal of the generator HG, and relay SP will also be picked up. That is to say, the same manually controlled circuit will be effective to energize both the stick relays SP and RP in 20 parallel. Under this condition, namely, a change of indication from clear to approach, the picking up of the stick relay SP serves no useful purpose and that relay will release at the end of its slow release period as soon as the acknowledging 25 switch ACK is restored to its normal position. The stick relay RP, however, once picked up will be retained energized after the switch ACK has been restored to its normal position over a stick circuit. This stick circuit for relay RP can be 30 traced from the positive terminal of the generator HG, along wire B32, front contact 61 of relay L, its own front contact 73, lower winding of relay RP, and thence to the negative terminal of the generator HG. Relay L and the stick relay 35 RP being now both energized, current will flow from the positive terminal of the generator HG over wire B32, front contacts 61 and 74 of relays L and RP, respectively, wire 57, winding 67 of magnet valve H, controller 58, wire 91, back contact 40 59 of relay SP, front contact 82 of relay RP, wires 93 and 89, front contact 63 of relay L, and thence to the negative terminal of generator HG and the magnet valve H will be reenergized and the whistle silenced. As long as the approach 45 indication continues, the stick relay RP remains picked up and the magnet valve H is energized over the circuit just traced.

In the event that clear traffic conditions are reestablished and relay MA is again energized continuously and the relay L is deenergized, the stick circuit for the relay RP is opened at the front contact 61 of relay L and relay RP is released. The winding 67 of the magnet valve H is now energized over the circuit first traced for 50 that winding which circuit includes the front contacts 48 and 54 of relay MA. Consequently, the whistle WS is not sounded at the change from approach indication to the less restrictive clear indication.

Returning to the assumption that the train is travelling under approach indication and that the stick relay RP is energized to complete the circuit to the winding 67 of the magnet valve H, I will further assume that traffic conditions 55 change from approach to stop and that both relays MA and L are deenergized. The stick circuit for the relay RP will be open at the front contact 61 of relay L and that relay will be released to open in turn the circuit to the winding 61 resulting in the whistle WS being sounded after a brief delay to call the engineman's attention to the change in the indication from approach to the more restrictive stop indication. To silence the whistle WS, the engineman will 60 operate the acknowledging switch ACK to close

the controller 70 for a brief interval and will then restore the switch to its normal position to close the controller 58. Controller 70 when closed completes the pick-up circuit for the two stick relays SP and RP the same as described 5 hereinbefore. This time the stick relay SP will be retained energized by current supplied from the positive terminal of the generator HG over wire B32, back contact 49 of relay MA, back contact 64 of relay L, wires 65 and 83, its own front contact 84, winding of relay SP and to the negative terminal of the generator HG. Relay RP will be retained energized over the circuit extending from the positive terminal of generator HG over wire B32, front contact 85 of relay SP, 10 bottom winding of relay RP, and to the negative terminal of generator HG. With both stick relays SP and RP picked up and both relays MA and L down, current will flow from the positive terminal of generator HG over wire B32, front contact 65 of relay SP, front contacts 73 and 74 of relay RP, wire 57, winding 67, controller 58, wire 91, a second front contact 86 of relay SP, and to the negative terminal of generator HG. Hence, the magnet valve H will be reenergized 25 and the whistle WS will be silenced. It is clear, therefore, that if the engineman acknowledges the operation of the audible signal WS upon a change from clear to approach indication, or upon a change from approach to stop indication 30 by operating the switch ACK, he may prevent the continuous operation of the whistle.

I will now assume that with the train proceeding under a stop condition, the traffic conditions change from stop to approach so that relay MA 35 is operating at code frequency and relay L is picked up. When this condition of relays MA and L is established, the stick circuit for the relay SP is open at the back contact 64 of relay L, and relay SP is released. The stick relay RP 40 continues to receive current over the front contact 61 of relay L and its own front contact 73, and hence remains energized. With relay RP picked up along with the relay L, the circuit to the winding 67 of the magnet valve H traced 45 heretofore under approach conditions is completed, and hence magnet valve H remains energized and the whistle WS is not sounded in response to the change from stop to approach indication. Upon a change from stop to clear indication the stick circuits for both relays SP and RP are opened and both relays are released, but the winding 67 of the magnet valve H now receives current over the normal circuit for that winding, and which circuit includes the front 50 contacts 48 and 54 of relay MA. Hence, the whistle WS is not sounded in response to a change from stop to clear indication. It follows that any change from a less restrictive to a more 55 restrictive indication causes the whistle WS to be operated, and it continues to operate until the engineman acknowledges the change by actuating the switch ACK. Upon a change from a less restrictive to a more restrictive indication, the whistle WS does not operate and no acknowledgement by the engineman is necessary.

In actual installations of systems of the type here involved it is not always convenient to locate the insulated rail joints 2 of Fig. 1 directly opposite each other, and, consequently, as the 70 train passes from one track section into the next successive track section there may occur a momentary loss of train control current with the result that the relay MA may release for a brief 75 interval. Such operation of the relay MA may

result in the momentary deenergization of the magnet valve H. The whistle delay WD is effective at such periods to prevent any sounding of the whistle WS before the relay MA is reenergized.

To explain the operation of the apparatus as a whole I will assume that the train V^a proceeds through the stretch of track shown in Fig. 1, the train V remaining standing in the section to the right of location C. Alternating current is continuously superposed on the direct current track circuit for the section to the left of location A and is also superposed on the direct current track circuit for the section A—B. Consequently, the relay MA of train V^a is picked up continuously as the train proceeds through the section to the left of location A and also as it proceeds through the section A—B. Under these conditions, the cab signal light G is illuminated to display a clear indication and the magnet valve H is energized to retain the whistle WS silent. When the train V^a enters section B—C, the alternating current superposed on the direct current track circuit for the subsection B—B¹ and also for the subsection B¹—C is coded and, consequently, the relay L of the train carried equipment is picked up continuously. Under these conditions, the indication displayed by the cab signal changes from green to yellow and the winding 67 of the magnet valve H becomes deenergized and the audible signal WS is sounded. The engineman will acknowledge this change of the indication in the cab signal by operating the switch ACK which causes the stick relay RP to be picked up with the result that the winding 67 of the magnet valve H is reenergized and the whistle silenced. As the train passes from the subsection B—B¹ into the subsection B¹—C, no change in the train carried equipment takes place. When the train V^a enters the section to the right of location C, the supply of train controlling current to the train V^a is shunted away by the wheels and axles of the train V and, consequently, both relays L and MA of the train V^a are deenergized. Under these conditions the cab signal displays red and the winding 67 of the magnet valve H is deenergized to cause the whistle WS to sound. The engineman will acknowledge this change in the indication of the cab signal by operating the switch ACK and both relays SP and RP are picked up, the magnet valve H reenergized and the whistle WS silenced.

It will be noted that operation of a code transmitter is required for the track section immediately to the rear of an occupied section only, and that code operation of the train carried relay MA is required only during the interval when a train occupies the section immediately to the rear of an occupied section. I have found that in actual railroad service these periods are only a small proportion of the time a train is on the road. Code operation of the equipment being required only for short periods, long life and reliability for such equipment are obtained. Furthermore, a less expensive construction for such devices is permitted than where such devices are normally operated under clear conditions and hence a material saving in first cost and maintenance is obtained.

Although I have herein shown and described only one form of trackway apparatus and only one form of train carried apparatus embodying my invention, it is understood that various changes and modifications may be made therein within the scope of the appended claims without

departing from the spirit and scope of my invention.

Having thus described my invention, what I claim is:

1. Railway traffic controlling apparatus comprising a section of railway track, a source of alternating current for said section, a code transmitter normally inactive, means governed by clear traffic conditions to supply current continuously from said source to the traffic rails of said section in series, means governed by approach traffic conditions to render said code transmitter active and to supply current from the source through the code transmitter to the rails of the section in series, a first and a second train carried relay, means for energizing said first relay continuously when alternating current flows continuously through the rails of the section occupied by the train and to operate said first relay at code frequency when the alternating current is coded, means for energizing said second relay continuously when the first relay is operated at code frequency; and a three-position cab signal controlled by said relays and arranged to display a clear indication when the first relay is energized continuously, to display an approach indication when said second relay is energized continuously and to display a stop indication when both relays are continuously deenergized.

2. Railway traffic controlling apparatus comprising a stretch of railway track divided into track sections, a direct current track circuit for each section responsive to traffic conditions of the section, a code transmitter for each section normally inactive, a first and a second controller governed by the track circuit and each operated to a first position when the section is unoccupied and to a second position when the section is occupied, means including the first position of said first controller for superposing alternating current on the track circuit for the section to the rear, means including the second position of the second controller for rendering the code transmitter active, means including the second position of the first controller for superposing alternating current coded by said transmitter on the track circuit for the track section to the rear, a first and a second train carried relay, means for energizing said first relay continuously when alternating current flows continuously in the track circuit occupied by the train and to operate said first relay at code frequency when the alternating current is coded, means responsive to such code operation of the first relay for energizing said second relay continuously, a first cab signal circuit including a front contact of the first relay, a second cab signal circuit including a front contact of the second relay, and a third cab signal circuit including a back contact of each of said relays.

3. Railway traffic controlling apparatus comprising a stretch of railway track divided into track sections, a direct current track circuit for each section; a wayside signal for each section adapted to display a clear, an approach and a stop indication in accordance with the conditions of the track circuits of the sections in advance of the signal, a code transmitter for each section but normally inactive, means including a first controller governed by the clear and approach positions of a signal for superposing alternating current continuously on the track circuit for the section to the rear of said signal, means including a second controller governed by the stop position of the signal for rendering the code trans-

mitter active, means including a contact member of the code transmitter and the stop position of said first controller for superposing coded alternating current on the track circuit to the rear of said signal, a first and a second train carried relay, means for energizing said first relay continuously when alternating current flows continuously through the rails of the section occupied by a train and to operate said relay at code frequency when the alternating current is coded, means for energizing said second relay continuously when the first relay is operated at code frequency; and a three-position cab signal controlled by said relays and arranged to display a clear indication when the first relay is energized continuously, an approach indication when said second relay is energized continuously and a stop indication when both relays are deenergized.

4. Railway traffic controlling apparatus comprising a section of railway track, a code transmitter normally inactive, means for at times supplying alternating current continuously to the traffic rails of the section in series, means for at times rendering said code transmitter active for supplying coded alternating current to said traffic rails in series, a first and a second train carried relay, means for energizing said first relay continuously when alternating current flows continuously through the traffic rails and to operate said first relay at code frequency when the alternating current is coded, a transformer having one-half of its primary winding excited with direct current over a front contact of said first relay and the other half excited over a back contact of said first relay, a rectifier interposed between the secondary winding of said transformer and said second relay, a less restrictive cab signal circuit including a front contact of the first relay, a more restrictive cab signal circuit including a front contact of the second relay and a still more restrictive cab signal circuit including a back contact of each of said relays.

5. Railway traffic controlling apparatus comprising a section of railway track, a source of alternating current for said section, a code transmitter normally inactive, means governed by clear traffic conditions to supply current continuously from said source to the traffic rails of the section in series, means governed by approach traffic conditions to render the code transmitter active and to supply current from the source through the code transmitter to the rails of the section in series, a first and a second train carried relay, amplifying apparatus on the train receiving energy from the traffic rails, a rectifier interposed between said amplifying apparatus and said first relay, a transformer having one-half of its primary winding excited with direct current over a front contact of the first relay and the other half excited over a back contact of said relay, a second rectifier interposed between the secondary winding of said transformer and the second relay, a clear cab signal controlled by a front contact of the first relay and a back contact of the second relay, an approach cab signal controlled by a front contact of the second relay only, and a stop cab signal controlled by a back contact of each of said relays.

6. Railway traffic controlling apparatus comprising a section of railway track, a source of alternating current of a given frequency, a code transmitter normally inactive, means for at times supplying current from said source continuously to the traffic rails, means for at times rendering said code transmitter active for supplying cur-

rent from said source to traffic rails coded at a given frequency, receiving means including a filter tuned to resonance at said given frequency of the alternating current to receive energy from the traffic rails, amplifying apparatus including an electron tube governed by the energy picked up by said receiving means, a source of high potential unidirectional current for the plate circuit of said tube, a source of low potential unidirectional current for the filament circuit of said tube, a first and a second train carried relay, a rectifier interposed between the amplifying apparatus and the first relay, means controlled by said first relay when operated for supplying current at a frequency corresponding to the frequency of operation, a second rectifier interposed between said last mentioned means and said second relay, a filter interposed between said source of high potential and the plate of said tube, and a choke coil interposed between said source of low potential and the filament of said tube whereby pulsations of the high or low potential sources are ineffective to energize said relays.

7. Railway traffic controlling apparatus comprising a section of railway track, a source of alternating current, means for at times supplying current from said source to the traffic rails of the section, train carried receiving means to receive energy from the traffic rails, amplifying apparatus including an electron tube governed by the energy picked up by the receiving means, a source of high potential unidirectional current for the plate circuit of said tube, a train carried traffic governing relay, a rectifier interposed between the amplifying apparatus and said relay for energizing said relay in response to alternating current flowing through the traffic rails, a filter including a reactor and a condenser interposed between the source of high potential and the plate of said tube, the connections of the reactor and condenser being arranged in such a manner that the failure of a connection will destroy the plate voltage of said tube, whereby pulsations of the high potential source are ineffective to energize said relay and said filter operates on the closed circuit principle.

8. Railway traffic controlling apparatus comprising a first and a second train carried relay; means located partly on the trackway for energizing the first relay continuously in response to energy received on the train from the trackway under clear traffic conditions to operate said first relay and to continuously energize the second relay under approach traffic conditions and to deenergize both relays under stop traffic conditions, a first and a second stick relay, manually controlled means for energizing said stick relays, means for subsequently holding the first stick relay closed as long as said second train carried relay is energized and for subsequently holding both stick relays energized as long as both train carried relays are deenergized, a magnet valve, a first circuit for said magnet valve including a front contact of the first train carried relay and a back contact of each of the stick relays; a second circuit for the magnet valve including a front contact of the second train carried relay, a front contact of the first stick relay and a back contact of the second stick relay; a third circuit for said magnet valve including a front contact of each of the stick relays, and an audible signal operated by said magnet valve.

9. Railway traffic controlling apparatus comprising a first and a second train carried relay; means located partly on the trackway for energizing

ergizing the first relay continuously in response to energy received on the train from the track-way under clear traffic conditions, to operate said first relay and to continuously energize the 5 second relay under approach traffic conditions and to deenergize both relays under stop traffic conditions; a first and a second stick relay, manually controlled means for energizing said stick relays, means for subsequently holding the 10 first stick relay closed as long as said second train carried relay is energized and for subsequently holding both stick relays energized as long as both train carried relays are deenergized, means for automatically releasing said second 15 stick relay and retaining the first stick relay energized in the event the second train carried relay becomes energized subsequent to both train carried relays being deenergized, a magnet valve, a first circuit for said magnet valve including 20 a front contact of the first train carried relay and a back contact of each of the stick relays; a second circuit for the magnet valve including a front contact of the second train carried relay, a front contact of the first stick relay and a back contact 25 of the second stick relay; a third circuit for said magnet valve including a front contact of each of the stick relays, and an audible signal operated by said magnet valve when deenergized.

10. Railway traffic controlling apparatus comprising, a track section, a source of alternating current, a code transmitter normally inactive, a first and a second contact member governed by 30 said transmitter; a normal contact for said first member and a normal and a reverse contact for said second member, a first and a second controller, means governed by safe traffic conditions in advance of said section for operating said controllers to a first position, means governed by 35 unsafe traffic conditions in advance of said section for operating said controllers to a second position; means including said source, the normal contact of said second member and the first position of said first controller for supplying alternating current continuously to the rails of the 40 section in series; means including the normal contact of said first member and the second position of said second controller for rendering said code transmitter active; and means including 45 said source, the reverse contact of said second member and the second position of the first controller for supplying coded alternating current to the rails of the section in series.

11. Railway traffic controlling apparatus comprising, a track section, a source of alternating current, a code transmitter normally inactive, means governed by clear traffic conditions in 50 advance of the section and rendered effective by the inactive condition of said code trans-

mitter to continuously supply alternating current from said source to the traffic rails of the section in series, means governed by approach traffic conditions in advance of said section to render said code transmitter active, and other means governed by approach traffic conditions in advance of said section and rendered effective by the active condition of said code transmitter to supply coded alternating current from the source to the traffic rails of the section in series. 10

12. Railway traffic controlling apparatus comprising, a track section, a source of alternating current, a code transmitter normally inactive, a contact member operated by said code transmitter, a first and a second circuit controller, 15 means governed by safe traffic conditions in advance of the section for operating said controllers to a first position, means governed by unsafe traffic conditions in advance of said section for operating said controllers to a second 20 position, means including said source and effective by the normal position of the contact member and the first position of said first controller for supplying alternating current continuously to the rails of the section in series, means including 25 the second controller in its second position for rendering the code transmitter active, and other means including said source and effective by the active condition of said contact member and the second position of said first controller for 30 supplying coded alternating current to the rails of the section in series.

13. Railway traffic controlling apparatus comprising, a first and a second track section, a direct current track circuit for each section including the traffic rails in series, a code transmitter for each section normally inactive, a contact member operated by said code transmitter, a first and a second circuit controller, means governed by the track circuit of the first section 35 when unoccupied to move said controllers to a first position, means governed by the track circuit of said first section when occupied to move said controllers to a second position, a source of alternating current, means including 40 said source and effective by the normal position of the contact member and the first position of said first controller for superposing alternating current continuously on the track circuit of the second section, means including the second position of said second controller for rendering the code transmitter active, and other means including 45 said source and effective by the active condition of the contact member and the second position of said first controller for superposing coded alternating current on the track circuit of 50 said second track section.

FRANK H. NICHOLSON.
